[57] CLAIM

The ornamental design for an automobile wheel, as shown.

DESCRIPTION

FIG. 1 is a front and right side perspective view of an automobile wheel showing my new design, the wheel being symmetrical about its axis;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

*Fig. 1**Fig. 2**Fig. 3**Fig. 4**Fig. 5**Fig. 6*
